Joseph. Beckel*

UNITED STATES PATENT OFFICE.

JOSEPH BECKEL, OF NEW YORK, N. Y.

APPARATUS FOR DISPLAYING STEREOSCOPIC PICTURES.

Specification of Letters Patent No. 22,695, dated January 25, 1859.

To all whom it may concern:

Be it known that I, JOSEPH BECKEL, of the city, county, and State of New York, have invented a new and Improved Stereo-

5 scopic Instrument for the Reception and Display of Stereoscopic Views; and I do hereby declare the following to be a correct description of the same, reference being had to the accompanying drawings, in which—
10 Figure 1 is a central vertical section, from front to rear of the apparatus; Fig. 2 is a front elevation of the same; and Fig. 3, a detail view of the endless chain of pictures.

15 My invention consists in the form of apparatus hereinafter particularly described by which a larger number of views may be packed and displayed in a case of the same dimensions than by any arrangement now 20 known or used.

In the drawings, the same part is marked in all the figures by the same letter of reference.

25 A marks the case or box; *a, a, a*, the revolving prism; B the handle of the prism; *b, b, b*, the endless chain of pictures; C a rest or stop to guide the fall of the pictures; D, *d, D*, semi-cylindrical concave at the bottom of the box; E, *E*, lenses; 1, 2, 3, 4, 5, 6, 30 7, pads or cushions on the corners of every alternate picture.

I make the prism *a, a, a*, with three or more sides or faces of pasteboard, wood or metal as preferred. This prism has journals which revolve in bearings in the side of the box. It is turned by means of the handle B. The faces of the prism correspond in size with the pictures to be exhibited. The pictures are arranged in an endless 40 chain *b, b*, and pass over the prism *a, a, a*, as

it is turned, in the direction indicated by the arrows. The picture which has last left the face of the prism, is received, as it descends, by the rest or stop C, which causes it to fall in the proper position upon those that have preceded it, as shown in Fig. 1. The pads 1, 2, 3, &c., cause the outer edges of the pictures to form a larger arc, in consequence of their being separated, than the inner edges, so that the whole series will conform 45 to the shape of the concave *D, d, D*, as shown. Owing to the shape of the concave the pictures will, of their own weight, and without the exertion of any considerable force, pass round from the back to the front 50 of the box, as the prism is revolved.

The instrument may be constructed so as to be capable of accommodating and showing in succession, from three to a hundred, or more, stereoscopic pictures. 60

Having thus fully described my invention what I claim, and desire to secure by Letters Patent, is—

1. In combination with an endless chain 65 of pictures, constructed and arranged as described the revolving prism *a, a, a* arranged and operating as described.

2. The rest or stop C arranged and operating as specified.

3. The concave *D, d, D* arranged and operating in the manner described. 70

4. The pads or cushions 1, 2, 3, 4, &c., arranged and operating as specified.

The above specification signed and witnessed this thirtieth day of December 1858. 75

JOSEPH BECKEL.
